METHOD FOR COLLECTING SOUND

Application filed August 18, 1930. Serial No. 475,964.

The present invention relates to a method for collecting sound, as by a microphone, for such uses as the recording of sound with motion pictures. The object is to collect such sound advantageously and effectively under conditions wherein the sound to be collected emanates successively from different places in the setting or scene.

The invention may be used by means of a microphone supporting device which will permit the easy and rapid moving about of the microphone to maintain it in close association with the respective sound sources during the time of use. The microphone will preferably be brought to a place over the heads of musicians, actors, etc., being photographed in a setting or scene, and moved about and maintained in close relation to the actors as they move about, or as the sound to be collected emanates from different parts of the scene, with the microphone and its supporting devices outside the picture camera range. By picture camera range in this connection I mean that effective range defined by the aperture plate in the camera and which limits the size and shape of the picture on the film.

A highly efficient form and character of a device for carrying out the present invention is shown herein. It is of such reasonably light weight and is otherwise so constructed that it may be moved about conveniently on the studio floor or out in the field. It may also be transported easily from place to place in disassembled, collapsed or knockdown condition, which is of notable importance when it is considered that in making motion pictures away from the studio, or "on location," the various apparatus necessary for the recording of both the picture and the sound must frequently be transported through woods, over streams, among rocky fastnesses, etc., by human labor, on mule back, by canoes, etc., the conditions often being most severe. Lightness, strength, durability under rough treatment, and a high degree of portability, together with the advantages of rapid and easy control by the operator, are the important features and objects of the present device. Other objects and advantages will appear hereinafter.

In the drawings Figure 1 is a side elevation of the device with a portion of the boom broken away interiorly to show that the boom proper may be, as it ordinarily is, longer proportionately than as illustrated;

Fig. 2 is a plan section of the base as on the line 2-2 of Fig. 1;

Fig. 3 is an enlarged fragmentary detail partly in section of any one of the casters and associated parts;

Fig. 4 is an enlarged fragmentary plan of the outer end of one of the base pipe sections;

Fig. 5 is an enlarged perspective of the construction directly supporting the boom;

Fig. 6 is an enlarged perspective of the device for holding the strut member adjustably;

Fig. 7 shows fragments of the parts of Fig. 5 partly in section;

Fig. 8 is a fragmentary enlarged side elevation of the middle portion of parts of the base;

Fig. 9 is a fragmentary bottom view of the parts of Fig. 8; and

Fig. 10 is a detail section of one of the locking devices on line 10-10 of Fig. 9.

The microphone proper is marked 15a in Fig. 1. It is mounted to tilt on the hollow body 15b containing electrical apparatus operatively associated with the microphone proper. For present purposes I will consider this unit as a whole, namely 15a and 15b, and marked 15, as the microphone.

The base of the device may be of various forms and constructions, and will ordinarily be mounted on three equally spaced-apart wheels as 16, of the caster type, to enable the device to be moved about easily, the wheels being of such substantial diameter as will provide freedom of movement over the obstructions ordinarily encountered.

I have shown the base 17 in a form enabling it to be collapsed or folded into smaller compass for transportation. There is a substantially triangular plate 20, which may be of sheet steel. Centrally on this is a fixture 21, which may be a casting. Fixture 21 is riveted to plate 20 and has three radially-extending notches 22, 23 and 24. Into these notches respectively extend the flattened ends

of pipe sections 25, 26 and 27 respectively, and rivets 28, 29 and 30 hold these pipe sections in place. Note that a riveted U-shaped strap 31 around pipe section 25 holds that pipe section against movement relative to plate 20. The other two pipe sections may swing on their respective rivets so as to occupy their dotted-line positions in Fig. 2.

Plate 20 is marginally provided with two locking devices for the pipe sections 26 and 27 respectively, and which hold these sections in their radially-directed positions shown in Fig. 2. Figs. 8, 9 and 10 show one of these locking devices. A strap 32 is formed to fit around the pipe section 26 or 27 and is welded to plate 20. The swiveled bolt 33 swings upward into notch 34 (Fig. 9) and the wing nut 33a holds the section 26 or 27 clamped tightly yet readily releasably in place. Note that the strap 32 is formed to provide a slightly restricted opening through which the pipe section must pass to and from its seat. The springiness of strap 32 thus holds the pipe section in place tentatively while the bolt 33 is being tightened.

The outer ends of the pipe sections 25, 26 and 27 are flattened (Figs. 1, 3 and 4) and vertically bored to accommodate the caster stem 35 provided with a ball bearing device 36.

Near the outer end of each pipe section 25, 26, and 27 a lug 38 is welded (Fig. 4) and then slotted at 39 to provide a yoke to receive the flattened end of a supporting pipe section 40. There are three of these sections 40, one for each section 25, 26 and 27.

A stud 41 is secured so as to upstand centrally on plate 20. On stud 41 a vertical pipe section 42 telescopes removably. A vertical pipe section 43 telescopes over section 42 and a clamping screw 44 holds these two sections together for ready separability. A three-pronged spider 44 is welded to section 43 and to the prongs of the spider are pivoted pairs 45 of strap-iron connection pieces 45a and 45b.

Between the short pipe sections 40 which are swiveled to the lugs 38 (Fig. 1) at the bottom and the bracing members 45a and 45b at the top there are pipe sections 46 which are rigidly secured to the parts 45a and 45b as by welding. The pipe sections 46 telescope into the sections 40 respectively and the clamping thumb screw at 47 holds each section 46 firmly yet releasably to the associated socket section 40.

According to the description thus far there is a rigid base in triangular form, the same being mounted on three wheels of the caster type, the base being substantially wide, being collapsible for transportation and storage, having a central upstanding stem, and bracing members extending therefrom to the marginal portions of the base. It is a skeleton framework which is light and strong and capable of being put into small compass.

Telescoping into the upper end of the vertical tube section 43 is a vertical tube section 50. The clamping screw at 51 holds these two pipe sections together firmly yet releasably. If screw 51 be released the tube 50 may turn 70 in tube 43. Tube 50 may be held at various elevations by means of the screw at 51 also.

Telescoping downwardly into the top of tube 50 is a tube or rod 52 held in any given position of vertical adjustment by means of 75 the clamping screw 53 on tube 50. Carried rigidly by the upright 52 is a hollow rectangular frame 54.

Referring to Figs. 5 and 7 this frame 54 has extending through it a shaft 55 which 80 has a reduced portion 55a, a further reduced portion 55b and a still further reduced portion 55c, and at the outer end of the latter is a collar 56 so secured to it as to prevent the shaft from being withdrawn. Screw 85 threads at 57 thread into the lug 58 which has a counterpart 58a, and through which the shaft also passes. These lugs 58 and 58a are spaced apart and are secured as by welding to a split pipe section or strap 59 surrounding the boom 60.

Fig. 7 shows that by turning the hand wheel 61 on shaft 55 in one direction the boom 60 will be clamped so that it may not move longitudinally, and that by turning 95 the hand wheel 61 in the opposite direction the boom will be released for such longitudinal movement through the strap 59. It is also apparent that the boom may at all times tilt in vertical planes through its swinging suspension by the rocking shaft 55.

Reverting to Fig. 1, the dotted line at 63 indicates meeting ends of tube sections 42 and 50. With the clamping screw at 51 released the boom may swing in horizontal 105 planes in any tilted position, the bearing being at 63.

At the rearward end portion of boom 60 is a split pipe section or clamping sleeve 64 controlled by the wheeled clamping screw at 110 65. Pivoted on that clamping screw is a strut rod or member 66 which is shown by dotted lines in Fig. 6. The rod or strut member 66 is held tightly (Fig. 6) by the eye member 67 through which rod 66 passes. The eye member 67 terminates in a bolt 68 which is seen extending through the hand wheel 69. There is a sleeve 70 on this bolt 68 and the construction is such that when the hand wheel is tightened on the sleeve 115 70 the rod 66 is clamped against the vertical wall 70a of the frame having a top wall 70b and a bottom wall 70c. By loosening the hand wheel 69 the rod 66 is released. This construction forms a sort of swivel connection since the angular relation of the rod is permitted to vary thereby. The parts 70b and 70c of the frame are welded to a split sleeve 75 carrying two lugs 76 and 77 welded thereto, and the clamping screw 78 threaded 125 130

into lug 76 operates to clamp the shell 75 on vertical pipe section 50. Fig. 1 shows a hand wheel 80 on the clamping screw 78.

The shell 75 (Fig. 6) may be moved upward on shaft 50 and held in any position thereon by the clamping screw 78. If one were to loosen the clamping screw at 51 and also the clamping screw at 80 the pipe section 50 could be elevated, and then if clamping screw 78 were tightened the shell 75 would rest on the top of pipe 43 and permit the boom to swing in horizontal planes. What I have just described is another method for seating pipe 50 for horizontal swinging movements of the boom, while also showing that pipe 50 may be raised to elevate the boom proper. Ordinarily the raising or lowering of the upper section 52 will meet all requirements for vertical elevation of the boom at the mast.

The boom proper is long and slender and is preferably as light as may be feasible. In my practice it is a piece of metal tubing. A length of about fifteen feet will be found appropriate in most instances. I show means for extending it somewhat, namely the extensible section 60a which telescopes into the forward end of the main section 60. A set screw at 82 will hold the section 60a at any degree of extension.

I have shown the microphone 15 as being suspended by a yoke or frame 84 from a grooved wheel 85 adapted to travel on the upper surface of the boom. At the end of section 60a is a grooved wheel or sheave 86.

A cord 87 secured at 88 to the frame 84 and passing over sheave 86 and then passing back over a pair of pulleys at 89 (Figs. 1, 5 and 7) enables the operator to move the microphone back and forth along the boom by drawing on one or the other section of the cord. Having positioned the microphone as desired he can make it secure by fastening the free ends of the cord to any convenient part of the construction.

The boom 60 contains several hooks or loops 90 through which the conductor cable 91 leads from the microphone back to the mast where there is a similar hook or eye 92.

A counterweight 95 is secured upon the end of the boom extending rearward from the mast. This counterweight will be such as to render the boom and microphone held thereby fairly well balanced.

During the operation of the device the operator is constantly desiring to move the microphone both as to elevation and in lateral directions. The forward end of the boom is always freely swinging in vertical planes except for the strut member 66 which holds it in any given position of vertical adjustment. Should the operator desire merely to raise and lower the boom he could do so by releasing the hand wheel 69 (Fig. 6) and then moving the rear end of the boom down or

up, the strut 66 sliding back and forth through the eye 67 shown in Fig. 6. Having placed the microphone at the desired elevation hand wheel 69 (Fig. 6) is tightened. The operator usually desires to swing the boom around as well as to elevate or lower its outer end, so ordinarily he will release the hand wheel at 51 (Fig. 1) as well as the hand wheel 69 (Fig. 6) as these operations free the boom for both vertical tilting and horizontal swinging.

It will be perceived that the operator is thus enabled to place the microphone as desired with a slight amount of effort, and in a very short time. He usually has his left hand on the rear end of the boom while with his right hand he manipulates the several controls, such as the hand wheels 51 and 69.

When it is desired to take the device down for transportation or storage the connection 64 at the left hand end of the boom in Fig. 1 can be slipped off, and the weight 95 can be removed. The upper standard section 52 can be lifted away. The pipe section 50 can be lifted away and the strut member 66 can be arranged along side it or taken off as desired. By loosening the hand wheels 47 near the bottom of Fig. 1 the bracing supports 46 can be withdrawn and the pipe section 43 can be lifted away from section 42, and the latter then lifted away from the base, or section 42 can be telescoped within section 43. The base can then be collapsed into the form shown by Fig. 2. The microphone can be lifted away bodily at any time.

According to the device shown the operator of the microphone may be rearward of, and is usually also a little to one side of the picture camera or cameras taking the scene, and may always be in an out-of-the-way position with respect to the camera men and their equipment, while having apparently all of the control desired for rapidly and quietly moving the microphone closer to or farther from the source of sound to be recorded as occasion suggests and from place to place horizontally as the actors move about or from one speaking character to another.

The device and method herein disclosed have gone into extensive use and have been found highly efficient and valuable in sound recording in connection with motion picture work.

I contemplate as being included in these improvements all such changes, variations and departures from what is thus specifically illustrated and described as fall within the scope of the appended claims.

I claim:

1. The method of collecting sound with a sound-translating device from a given setting where the sounds to be translated emanate in close succession from various sources located at different portions of the setting, which consists in moving the sound-trans-

- lating device back and forth and about in a
succession of movements from one portion of
the setting to another where the sound to be
collected is successively about to emanate and
5 immediately before the emission of the sound
to be collected, while maintaining the trans-
lating device, during the collecting, substan-
tially close to the sources respectively where
the sound to be collected emanates.
- 10 2. In sound recording synchronized with
motion pictures taken by a camera from a
setting in which the sound to be recorded
emanates successively from different portions
15 of the setting, the combination with a sound
translating device of means for moving same
easily and freely about the setting and suc-
cessively into close proximity with and above
the source of sound to be recorded while main-
taining the translating device out of the range
20 of the camera taking the motion pictures.
